UNITED STATES PATENT OFFICE.

ALFRED N. EDEBURN, OF CLEVELAND, OHIO, ASSIGNOR TO THE CLEVELAND GALVANIZING WORKS, OF CLEVELAND, OHIO, A CORPORATION OF OHIO.

CHAIN-LINK.

1,211,421.

Specification of Letters Patent.

Patented Jan. 9, 1917.

Application filed June 14, 1915. Serial No. 34,085.

To all whom it may concern:

Be it known that I, ALFRED N. EDEBURN, a citizen of the United States, resident of Cleveland, county of Cuyahoga, and State of Ohio, have invented a new and useful Improvement in Chain-Links, of which the following is a specification, the principle of the invention being herein explained and the best mode in which I have contemplated applying that principle, so as to distinguish it from other inventions.

My invention relates to links and blanks therefor for chains, said invention consisting specifically in an improvement in the construction shown, described and claimed in U. S. Letters Patent No. 955,129, issued April 19, 1910, to Irving A. Brown.

The object of the invention is to provide a link construction of the above-named character which will be economical of manufacture and efficient in operation.

The said invention consists of means hereinafter fully described and particularly set forth in the claims.

The annexed drawing and the following description set forth in detail certain means embodying my invention, the disclosed means, however, constituting but one of various mechanical forms in which the principle of the invention may be employed.

In said annexed drawing:—Figure 1 represents a plan of the primary blank forming part of my invention. Fig. 2 represents a plan of the secondary blank forming part of my invention. Fig. 3 represents a plan of a complete link embodying my invention. Fig. 4 represents a side elevation of such link. Fig. 5 represents a plan of such link with parts broken away to show the interior construction thereof, the plane upon which the parts are broken being indicated by the lines V—V in Fig. 4. Fig. 6 represents a section taken upon the plane indicated by line VI—VI in Fig. 4 and viewed in the direction indicated by the arrows. Fig. 7 represents a plan of a modified form of primary blank. Fig. 8 represents a plan of the secondary blank in the modified form of construction. Fig. 9 represents a plan of a complete link embodying the modified form of my invention. Fig. 10 represents a side elevation of the link shown in Fig. 9. Fig. 11 represents a section taken upon the plane indicated by line XI—XI in Fig. 10 and viewed in

the direction indicated by the arrows. Fig. 12 represents a section taken upon the plane indicated by line XII—XII in Fig. 10 and viewed in the direction indicated by the arrows. Fig. 13 represents a perspective view of two links connected with each other and embodying my invention. Fig. 14 represents a perspective view of two joined links constructed in accordance with the disclosure in the above-named Letters Patent.

It has been found that when chain consisting of links constructed in accordance with the above-named patent and illustrated by Fig. 14, is subjected to a given amount of tension, the end portions *a* tend to bend outwardly, and when this tension is sufficient, such outward bending actually takes place with a result that the extremities of the section of metal of which each link is composed, project laterally from the link and form obstructions which frequently interfere with the proper functioning of the chain. To overcome this objection, I modify the construction of the above-named patented link in a manner which I shall now describe.

In forming the link, I first take a straight bar of metal 1, which may consist of wire or other suitable material, and off-set its end portions 2, 2, so that they will extend in opposite directions with reference to the blank's axis, as shown in Fig. 1. The blank in this form I will designate as the primary blank. This primary blank is then bent so as to form two loops 3, 3, lying in substantially the same plane, the end-portions of said bar or rod lying intermediately of the ends of the loops, extending beyond each other and having their off-sets 2, 2, extending in opposite directions with reference to the axis of the structure so formed, as shown in Fig. 2. The structure so formed, I will designate as the secondary blank. This blank is then bent so as to bring the two loops 3, 3, adjacent to each other at one end of the link and to cause the other end of the link to be formed into an eye of which the end portions 2, 2, of the section form a part, as shown in Fig. 4. The form of the secondary blank is, however, such that the main part of such eye-forming end-portions lie upon opposite sides of a longitudinal plane, perpendicular to the loops 3, but the extremities of said eye-forming portions respectively, lie upon sides of said plane oppo-

site those upon which said main portions of said eye-forming portions lie. Furthermore these extremities are in a position in which they may be intersected by a line perpendicular to said longitudinal plane. As a result of this method of producing the link structure, when sufficient tension is applied to the link, and these end portions tend to move outwardly or laterally of the link, they 10 will engage each other, as will be clearly understood from an inspection of Figs. 5 and 6, and such engagement will prevent such outward or lateral movement and therefore eliminate the possibility of the previously mentioned lateral projection from the 15 eye of the loop before the actual rupture of the link occurs.

The above described construction provides for the formation of the link in such a manner that the engaging parts will be in contact with each other over a comparatively small surface. When it is desired to secure a greater amount of superficial contact than is so provided, I adopt the modified form of 20 construction illustrated by Figs. 7 to 12 inclusive. In this modified structure I not only off-set the end portions 2, but extend such off-set portions in the general direction of the blank by the provision of additional 25 end portions 4, 4, as shown in Fig. 7, when I form the primary blank. In this event, the secondary blank assumes the form shown in Fig. 8, and when this secondary blank is bent to form the complete link, the end-portions 30 4, 4, will be in contact or tend to be in contact with each other along the line 5, shown in Figs. 9 and 11, when the link is in tension. This, as it will be observed, gives a larger superficial contact of these end-portions 35 and thus insures to a greater degree, the engagement of these parts and the prevention of the outward distortion heretofore described.

While I have above indicated that the 40 off-sets are formed in the primary blank, it will be readily understood that where automatic machinery is employed to form these links, it might be more expedient to form the off-sets after or during the operation of forming the secondary blank. Such a deviation from the described process, will not, as will be readily understood, depart from the 45 principles of my invention.

Having fully described my invention, 50 what I claim and desire to secure by Letters Patent is:—

1. A primary chain link blank consisting of a section of wire or the like, having its end portions respectively off-set in opposite 55 directions with reference to the blank's axis, the extremities of such end portions extend-

ing in the general direction of the main part of said blank.

2. A secondary chain link blank comprising a section of wire or the like bent to form 60 two loops lying in substantially the same plane, the end portions of such sections extending laterally in opposite directions from an axis of the blank.

3. A secondary chain link blank comprising a section of wire or the like bent in opposite directions to form two symmetrical loops lying in substantially the same plane, the end portions of such section extending laterally of and in opposite directions from 75 an axis of the blank, and over the outer portion of the loop of which the other end portion forms a part.

4. A chain link comprising a section of wire bent to form two adjacent loops at one 80 end of the link and bent to form an eye at the other end of such link of which the end-portions of said section form a part, the main part of such eye-forming end-portions lying upon opposite sides of a longitudinal 85 plane perpendicular to said loops, and the extremities of said eye-forming portions respectively, lying upon sides of said plane opposite those upon which said main portions thereof lie.

5. A chain link comprising a section of wire bent to form two adjacent loops at one 90 end of the link and bent to form an eye at the other end of such link of which the end-portions of said section form a part, the main part of such eye-forming end-portions 95 lying upon opposite sides of a longitudinal plane perpendicular to said loops, the extremities of said eye-forming portions respectively, lying upon sides of said plane 100 opposite those upon which said main portions thereof lie; said extremities being both intersected by a line perpendicular to said longitudinal plane.

6. A chain link comprising a section of 105 wire bent to form adjacent twin loops at one end of said link, the ends of said section extending past each other and lying side by side, such ends being bent to form an eye at the other end of said link, and the portion of 110 said section that connects such loops passing around the outside of such ends and crossing from one side of one loop to the opposite side of the other; the extremities of said section being placed so that they will tend to 115 engage each other when the link is subjected to tension.

Signed by me, this 22 day of May, 1915.
ALFRED N. EDEBURN.
